UNITED STATES PATENT OFFICE

HENNING GUSTAV FLODIN, OF STOCKHOLM, SWEDEN

MEANS FOR REGULATING THE ELECTRODES IN REVERSIBLE ELECTRIC FURNACES

Application filed July 31, 1929, Serial No. 382,467, and in Sweden April 30, 1928.

This invention relates to arrangements for regulating the position of the electrodes in tilting electric furnaces by means of cables connecting the electrodes with one or more regulators outside the furnace, which may be of any known type, for instance hydraulic or electric regulators, winding drums, winches or the like.

The object of the present invention is to provide for the tilting of the furnace without affecting the position of the electrodes and this object is attained by an arrangement in which the cables from the regulators pass over stationary pulleys mounted independently of the furnace to pulleys on the furnace in such a manner that the point where the cables leave the said stationary pulleys is substantially on the tilting axis of the furnace.

In the accompanying drawing:

Figure 1 is a vertical projection of one form of construction of the means for carrying out the method, and

Figure 2 is the same seen from above.

A regulator 1 of a known type, an Arcuator regulator for instance, is mounted on a stationary wall. The draw-lines or chains 2, 3 are at either side of the furnace led over pulleys 4, 5 placed on a stationary platform, and further over discs 6, 7, 8 on the furnace, and finally wound once or several times on the discs 9 and fixed thereto. Each of the discs 9 is fixed on a spindle 10, to which are fixed two pulleys 11, 12 having lines 13 wound and fixed on them. These lines 13 pass over pulleys 14 and are fixed to the contacts of the electrodes.

The distance between the pulleys 4, 5 and the discs 6, 7 corresponds to the radius of an arc 18 described by the point where the lines leaving pulleys 4, 5 make contact with discs 6, 7 so that the length of the line remains substantially unaltered between the said pairs of pulleys and discs during the movements of the furnace to and from a tilted position.

Among other things, the invention offers the advantage of doing away with regulators fixed on the furnace, such regulators preventing an accessibility to, and control of the vault 50 of the furnace, which control is necessary

especially in furnaces for producing iron direct from ore.

The invention is not restricted to the form of construction described and shown, which can be modified without departing from the spirit of the invention, the characteristic feature of which is the connection between the regulator and the furnace, respectively, the electrodes, by means of draw-lines or chains so arranged that they do not displace the electrodes during the tilting and return of the furnace.

Having now described my invention, what I claim as new and desire to secure by Letters Patent is:

1. Arrangement for regulating the position of the electrodes in tilting electric furnaces by means of cables connecting the electrodes with regulators outside the furnace comprising pulleys mounted apart from said furnace and stationary with respect thereto and discs mounted on said furnace, said cables being guided by said pulleys and discs and leaving said pulleys at points substantially on the tilting axis of said furnace.

2. Arrangement according to claim 1 comprising spindles rotatably mounted on said furnace, discs fixed on said spindles and fastened to the furnace end of said cables, pulleys fixed on said spindles and other cables fastened thereto and to the electrodes of said furnace.

In testimony whereof I have signed my name to this specification.

HENNING GUSTAV FLODIN.
